CLAIM

The ornamental design for a LAMP, as shown and described.

DESCRIPTION

FIG. 1 is a perspective view of a LAMP, showing my new design;

FIG. 2 is a front view thereof;

FIG. 3 is a rear view thereof;

FIG. 4 is a side view thereof;

FIG. 5 is an opposite side view thereof;

FIG. 6 is a top view thereof; and

FIG. 7 is a bottom view thereof.

The broken lines depict portions of the LAMP that form no part of the claimed design.

1 Claim, 7 Drawing Sheets
